CLAIM

I claim the ornamental design for package for crab crackers, as shown.

DESCRIPTION

The file of this patent contains at least one drawing or photograph executed in color. Copies of this patent with color drawing(s) or photograph(s) will be provided by the Patent and Trademark Office upon request and payment of necessary fee.

FIG. 1 is a front/left-side perspective view of a package for crab crackers showing my new design;

FIG. 2 is a left-side elevational view thereof;

FIG. 3 is a right-side elevational view thereof;

FIG. 4 is a top plan view thereof;

FIG. 5 is a bottom plan view thereof;

FIG. 6 is a front elevational view of a front panel therefor; and,

FIG. 7 is a rear elevational view of a rear panel therefor.
